US0D1071839S

(12) **United States Design Patent** (10) **Patent No.:** **US D1,071,839 S**
(45) **Date of Patent:** **** Apr. 22, 2025**

(54) **BATTERY ATTACHMENT**

(71) Applicant: **ANNEX PRODUCTS PTY. LTD.**,
South Yarra (AU)

(72) Inventor: **Leigh Ryan**, South Yarra (AU)

(73) Assignee: **ANNEX PRODUCTS PTY. LTD.**,
South Yarra (AU)

(**) Term: **15 Years**

(21) Appl. No.: **29/886,603**

(22) Filed: **Mar. 10, 2023**

(51) LOC (15) Cl. **13-02**

(52) U.S. Cl.
USPC **D13/118; D13/103**

(58) **Field of Classification Search**
USPC D13/102-108, 110, 118, 119, 184, 199;

CLAIM

The ornamental design for a battery attachment as shown and described.

DESCRIPTION

FIG. 1 is a rear perspective view of a battery attachment in accordance with my new design;

FIG. 2 is a front elevation view of the battery attachment of FIG. 1;

FIG. 3 is a rear elevation view of the battery attachment of FIG. 1;

FIG. 4 is a right side elevation view of the battery attachment of FIG. 1;

FIG. 5 is a left side elevation view of the battery attachment of FIG. 1;

FIG. 6 is a top plan view of the battery attachment of FIG. 1; and,

FIG. 7 is a bottom plan view of the battery attachment of FIG. 1.

The broken lines depict portions of the battery attachment that form no part of the claimed design.

1 Claim, 5 Drawing Sheets
